(57) **CLAIM**

The ornamental design for a display screen with graphical user interface for managing customized messaging to a set of individuals, as shown and described.

DESCRIPTION

A portion of the disclosure of this patent document contains material to which a claim for copyright is made. The copyright owner has no objection to the reproduction of the patent document or the patent disclosure as it appears in the U.S. Patent Office records, but reserves all other copyright rights whatsoever.

FIG. 1 is a front view of a first image in a sequence for a display screen with graphical user interface for managing customized messaging to a set of individuals;

FIG. 2 is a second image thereof; and,

FIG. 3 is a third image thereof.

The broken line showing of a display screen and the other broken lines showing elements of the graphical user interface illustrate portions of the article and do not form part of the claimed design.

The appearance of the graphical user interface transitions sequentially between the images shown in FIGS. 1-3. The process or period in which one image transitions to another forms no part of the claimed design.
